ALFRED HUTTON AND SHERMAN MILLER, OF SCHENECTADY, NEW YORK

FIRE DOOR APPARATUS

Application filed October 19, 1929. Serial No. 400,976.

This invention relates to apparatus for operating fire doors of locomotive boilers, and other furnaces, and more particularly, to such form of apparatus wherein the doors are pivoted to swing laterally and vertically.

An object of the invention is to provide improved means whereby fire doors of the type indicated can be manually raised, automatically latched in selected positions, and manually released from latched positions.

Another object of the invention is to provide means for progressively increasing the leverage applied to lift fire doors of the type indicated, in accordance with the increase of weight imposed on the lifting lever as the doors are raised.

A further object of the invention is to provide fire door actuating means which can be operated either by fluid pressure or manually, as desired; which is economical to manufacture, install, and maintain; and which is highly efficient in operation.

Other objects of the invention will hereinafter readily appear.

The improvement claimed is hereinafter fully set forth.

In the accompanying drawing: Figure 1 is a view in front elevation of fire door apparatus embodying the invention, the parts being shown in full lines, with the doors in closed position, and in dot and dash lines with the doors in open position; Fig. 2, a side view, in elevation, of the construction shown in Fig. 1; and Fig. 3, a sectional view taken on the line III-III of Fig. 2.

In the practice of the invention, referring descriptively to the specific embodiment thereof which has been selected for exemplification herein, the fire door opening is closed by two butterfly fire doors 10 and 11 which meet at the vertical center line of the opening. To provide for lateral vertical opening of the doors, each door is pivoted at its top to a pivot pin 13, which has one end fastened in the door frame 14, and its other end projecting into a suitable bore formed in an arm 14a at the top of each door. The pivoted arms 14a of the doors are each provided with gear segments 15 and 16 which mesh

together, to effect simultaneous opening and closing of both doors.

To enable the doors to be operated by fluid pressure there is provided a cylinder 17, in which works a piston 18, connected by a pin 19, to a link 20, pivotally connected by a pin 21, to a lug 22, on the arm 14a of door 10. When it is desired to operate the doors by fluid pressure, fluid under pressure is admitted to one end of the cylinder through a pipe 23, by a valve (not shown) of any suitable type, preferably operated by a pedal device, as indicated in U. S. Patent to A. G. Elvin, et al., #1,186,978 of June 13, 1916.

To enable the doors to be manually operated a bell crank lever is provided. This lever comprises a handle arm 24, a fulcrum shaft 25, and lifting arm 26. The shaft 25 is journalled in a suitable bore provided in a lug 27 depending from the cylinder casting. One end of the shaft projects beyond the inner side of the lug 27, and has the lifting arm 26 rigidly connected to it, and the other end of the shaft projects beyond the outer side of the lug, is squared, and fits in a square opening in the handle arm. A nut 25a serves to secure the handle arm on the fulcrum shaft. The door 11 is provided with an abutment adapted to be engaged by the lifting arm 26 of the lever to effect manual lifting of the doors. This abutment comprises a pin 28 fastened at one end to the door 11, a roller 29, journalled on the pin, and a nut 30, for retaining the roller on the pin. From the foregoing description, it will be obvious that when the handle arm of the lever is manually pressed downwardly both doors will swing vertically and laterally on their pivot pins to open position.

To provide for progressively increasing the leverage applied by the hand lever to compensate for the increase in weight imposed on the lifting arm as the doors are raised, the axis of the fulcrum shaft 25 of the lever is made eccentric to the axis of the pivot pin 13 of the door 11, so that as the doors are raised the abutment roller 29 moves inwardly along the lifting arm 26.

To enable the doors to be fastened in fully open, and partially opened positions, a latch-

ing means is provided. This means comprises a quadrant or bar 31, pivoted at its top to a pin 32, fastened at one end to a cylindrical boss 32a on the cylinder casting and having a nut 33 at its other end for retaining the quadrant. The quadrant projects through a slot 34 formed in the handle arm 24 of the lever and is provided with notches 35 and 35a, adapted to engage a pin 36 which 10 extends transversely across the slot 34. A spring 37 is provided for urging the quadrant outwardly to insure engagement of the notches with the pin 36. The spring comprises a straight leg 37a, bearing on the inner edge of the quadrant, a spiral 37b coiled on the boss 32a on the cylinder casting, and a straight leg 37c, bearing on the underside of a lug 37d projecting from the cylinder casting. To release the lever from latched 15 positions a handle 38 is provided at the bottom end of the quadrant.

From the foregoing description it will be seen that when the arm 24 of the hand lever is moved downwardly to open the doors the 20 spring 37 will automatically move the quadrant outwardly engaging the notch 35 with the pin 36, when the doors are partially open. If the lever is then released the doors will be latched in partially open position. If the lever is moved further downwardly to fully 25 open the doors, the quadrant will move outwardly engaging the notch 35a with the pin 36, thus latching the doors in fully open position as shown in dot and dash lines in 30 Figure 1. To release the doors from latched positions, the operator has merely to grasp the handle 38 and push the quadrant inwardly, whereupon the doors will drop by gravity to closed position.

While one of the preferred forms of construction has been shown, it is obvious that many variations in procedure, and in the form, arrangement and construction of the parts can be made, and the invention is not 40 therefore limited to the particular embodiment disclosed, but includes such changes and modifications as come within the spirit and scope of the invention as set forth in the appended claims.

The invention claimed and desired to be secured by Letters Patent is:

1. In a fire door apparatus, the combination of a fire door adapted to open laterally and vertically, a pivot for the door, a lever having two arms for swinging the door on its pivot, a pivot fulcruming the lever, and means on the said door operably engaging one arm of the lever, the axis of the door pivot and the axis of the lever pivot being spaced one from the other to effect the gradual approach of said means toward said lever pivot during the opening of the door.

2. In a fire door apparatus, the combination of a fire door adapted to open laterally and vertically, a pivot for the door, a lever

having two arms for swinging the door on its pivot, a pivot fulcruming the lever, and means on the said door operably engaging one arm of the lever, the axis of the door pivot and of the lever pivot being substantially parallel and spaced one from the other to effect the gradual approach of said means toward said lever pivot during the opening of the door.

3. In a fire door apparatus, the combination of a door frame; a door; a pivot supporting the door for opening movement laterally and vertically in a plane parallel to the frame; a lever having two arms for opening the door; a pivot fulcruming the lever; and means on said door operably engaging an arm of the lever, the axis of the door pivot and the axis of the lever pivot being spaced one from the other whereby said means will gradually approach said lever pivot during the opening of the door.

4. In a fire door apparatus, the combination of a door frame; a door; an abutment on the door; a pivot supporting the door for swinging movement laterally and vertically in a plane parallel to the frame; and a lever having a handle arm, a fulcrum shaft having its axis spaced from the axis of the door pivot, and a lifting arm disposed to engage the abutment on the door to effect opening of the same whereby said abutment will gradually approach said lever fulcrum when the door is being opened.

5. In a fire door apparatus, the combination of a door frame; a door; an abutment on the door; a pivot supporting the door for swinging movement laterally and vertically in a plane parallel to the frame; a lever comprising a handle arm having latching means, a fulcrum shaft having its axis spaced from the axis of the door pivot, and a lifting arm disposed to engage the abutment on the door to effect opening of the same, whereby the said abutment will gradually move toward the fulcrum during the said opening of the door; a pivoted bar having latching means; and means adapted to automatically move the bar to engage its latching means with the latching means of the lever, whereby the lever may be latched in open position.

6. In a fire box door apparatus, the combination of a door; a pivot for said door adapting the same for vertical lateral opening; an abutment on the door; a lever comprising an arm having a handle and latching means, a fulcrum shaft separate from and independent of said pivot, and a lifting arm disposed to engage the abutment on the door to effect the opening of the door; a bearing carried by an immovable part of the apparatus in which the fulcrum shaft is journaled; and a pivotally mounted bar supported above and extending below said handle and having latching means adapted to engage the latching means of the lever to latch the lever in

position to hold the door open, the lower end of said bar serving as a handle for manually moving the bar to release its latching means from latching engagement with the latching means of the lever.

7. In a fire door apparatus, the combination of a door frame; a door adapted to open vertically and laterally in a plane parallel to the frame; an abutment on the door; a lever having two arms, for opening the door, one of said arms operably engaging said abutment; a latch member provided on the other of said arms; a bar-shaped latch member adapted to engage the latch member of the lever pivoted above, and extending downwardly across, and below the lever, providing a part at the lower end thereof for the application of force to disengage said latch members; and a spring acting on said bar-shaped latch member for automatically engaging said latch members to hold the door in open position.

8. In a fire door apparatus, the combination of a door frame; a door adapted to open vertically and laterally in a plane parallel to the frame; an abutment on the door; a lever having two arms, for opening the door, one of said arms operably engaging said abutment, the other of said arms being provided with a latch part and serving as a handle member; a bar-shaped member provided with a latch part adapted to engage the latch part of said handle member, pivoted above, and extending downwardly across and below, the lever; a handle at the lower end of said bar-shaped member for manually disengaging said latch parts, one of said members extending through a slot formed in the other of said members; and a spring acting on said bar-shaped member for automatically engaging said latch parts to hold the door in open position.

9. In a fire door apparatus, the combination of a door frame; a door adapted to swing vertically and laterally in a plane parallel to the frame; a pivot pin for mounting the door; an abutment on the door; a lever having two arms for opening the door, one of said arms operably engaging said abutment, the other of said arms serving as a handle; a pin separate and independent of said first mentioned pin and door for supporting the lever; and a bearing carried by an immovable part of the apparatus supporting said last mentioned pin.

10. In a fire door apparatus, the combination of a door frame; a door adapted to swing vertically and laterally in a plane parallel to the frame; a pivot pin for mounting the door; an abutment on the door; a lever having two arms in spaced vertical planes for opening the door, one of said arms operably engaging said abutment, the other of said arms serving as a handle; a pin separate from and independent of said first mentioned pin

and door for securing the arms together in said spaced relation; and a bearing carried by an immovable part of the apparatus within the space between said arms supporting said last mentioned pin.
